6 Claims. (Cl. 103—38)

1

The present invention relates to hydraulic pumps, and more specifically to an improved mechanism for automatically controlling the volumetric output of variable delivery hydraulic pumps.

Ordinarily, variable delivery hydraulic pumps, particularly those of the radial piston type, are provided with a flow-controlling member movable within the pump casing between positions of concentricity and eccentricity with respect to the pump rotor, whereby to vary the stroke of the associated pumping pistons to thus control the volume of fluid displaced by the pump. Movement of the flow-controlling member of the pump is occasioned by forces applied thereto by a variable tension compression spring arranged to act upon one side of the flow-controlling member to move the same from a concentric or neutral position toward a full delivery eccentric position. Positioned in opposing relationship to the spring are one or more fluid-pressure-responsive pistons or plungers which are ordinarily arranged to receive fluid pressure from a given point within a hydraulic circuit to which pressure fluid is supplied by the pump. Such pistons or plungers function to shift the flow-controlling member of the pump toward its neutral, no-delivery position in opposition to the spring, and in response to a predetermined high pressure within the hydraulic system or circuit fed by the pump. Alternatively, the fluid-pressure-responsive pistons or plungers may be arranged so as to receive pressure fluid in response to a predetermined movement of a hydraulic motor or ram connected within the hydraulic system in which the pump is interposed, in order to automatically decrease the volumetric output of the pump in response to a predetermined movement of the ram or motor which is actuated by the pump. Generally, the pistons or plungers of this character are referred to as servo-motor controls.

In operation, assuming that the pump is driven at relatively high speeds and is arranged to supply pressure fluid to a reciprocating hydraulic press ram, the spring functions to initially shift the flow-controlling member of the pump toward its maximum delivery position to initiate a relatively rapid closing cycle within the associated press ram. During movement of the ram toward a work-engaging position, the pump is conditioned to deliver a maximum volume of fluid, but as the ram approaches or engages a workpiece and resistance is offered thereby to continued movement of the ram, pressure within the output of delivery of the pump increases, and the servo-

2

motor pistons or plungers then function to shift the flow-controlling member of the pump back toward a neutral, no-delivery position. Actually, the flow-controlling member does not fully reach a neutral position, but attains a relatively short-stroke position, in order to maintain a constant holding pressure within the hydraulic circuit to compensate for slippage within the pump or leakage within the circuit controlled thereby.

10 The primary objection to controls of this type arises through their inability to properly control the flow of fluid from the pump when the pump is idling at relatively low speeds, wherein there is very little, if any, pressure exerted by fluid being displaced by the pump. At idling speeds, the spring which is conditioned to shift the flow-controlling member of the pump toward its full delivery position is unopposed by any of the servo-motor pistons, due to the absence of sufficient fluid pressure within the pump discharge to actuate the servo-motor pistons, and, therefore, the flow-controlling member is maintained in a full delivery position when the pump is in an idling condition.

25 Accordingly, it is the primary object of the present invention to provide, in association with the pressure-responsive pistons or plungers of a servo-motor control, a spring and pressure-actuated plunger which is effective to maintain the flow-controlling member of a pump on a short-stroke delivery position when the pump is idling at relatively low speeds insufficient to establish a predetermined pressure output of the pump, and which, upon normal operating speeds of the pump, is actuated by pressure fluid from the pump to permit the latter to be conditioned to discharge pressure fluid at full delivery, and to permit normal operation of the usual servo-motor pistons or plungers of the pump control.

30 It is another object of the invention to provide a limit stop for the piston stages of a servo-motor control which is arranged to shift the flow-controlling member of the pump to a short-stroke delivery position in the absence of a predetermined pressure within the discharge of the pump.

45 It is another object of the invention to provide a limit stop for the piston stages of a servo-motor control which is arranged to shift the flow-controlling member of the pump to a short-stroke delivery position in the absence of a predetermined pressure within the discharge of the pump to prevent undesired displacement of fluid from the pump at idling speeds, but which is movable in response to a build-up in pressure within the pump discharge during normal operating speeds of the pump to an inactive position permitting actuation of the flow-controlling member of the pump by the usual spring and servo-motor controls of the pump.

50 For a further and more detailed understanding of the present invention and the various addi-

tional objects and advantages realized therefrom, reference is made to the following description and the accompanying drawings, wherein:

Fig. 1 is a diagrammatic view of a hydraulic circuit including a variable delivery pump having the present pump control associated therewith;

Fig. 2 is an enlarged vertical sectional view taken through the piston end of the pump control;

Fig. 3 is a diagrammatic vertical sectional view of the pump conditioned on short-stroke idling position; and

Fig. 4 is a similar view showing the pump conditioned on high pressure neutral or holding position.

Referring now to the drawings, the numeral 10 designates generally the outer casing of a variable delivery hydraulic pump. Enclosed within the casing 10 is a circular primary rotor 11 which is arranged to be driven in rotation by a drive shaft and motor assembly, not shown. The rotor 11 is formed with a plurality of radially disposed cylinders 12 which open outwardly at the periphery of the primary rotor 11, and which terminate at their inner ends in relatively smaller diameter ports 13. The rotor 11 and its ports 13 are arranged to rotate about a relatively stationary valve pintle 14 in which are formed separate inlet and outlet passages, 15 and 16, respectively. In the position shown in the drawings, the pump is arranged to receive fluid through the inlet passage 15 and to discharge fluid from the outlet passage 16. Slidably carried within each of the cylinders 12 is a reciprocating pumping piston or plunger 17 which terminates at its outer end in a crosshead 18 which is connected with an annular secondary rotor 19. In the usual manner, the secondary rotor is rotatably supported within an annular shift ring or flow-controlling member 20 which is arranged to slide longitudinally of the pump casing 10 between positions of concentricity and eccentricity with respect to the primary rotor 11.

As will be understood, the elements of the pump heretofore described are those which normally comprise the usual radial piston variable delivery hydraulic pump, whose operation will be well understood by those skilled in the art. So long as the shift ring 20 and the secondary rotor 19 occupy concentric positions with respect to the primary rotor 11, there is no reciprocating motion of the pumping pistons 17, and consequently, no displacement of fluid between the inlet and outlet ports of the pump. However, as the shift ring 20 is displaced leftwardly, as viewed in the drawings, and as the primary and secondary rotors are rotated, the pistons 17 are forced to reciprocate within the cylinders 12 of the primary rotor to thus draw fluid inwardly of the cylinders from the inlet passage 15 and to force fluid outwardly of the cylinders by way of the outlet passage 16. The greater the degree of eccentricity between the primary and secondary rotors, the greater the stroke of the pistons 17, and consequently, a greater volume of fluid is displaced by the pump when the shift ring occupies its extreme left-hand position, as shown in Figs. 1 and 2 of the drawings, than when the shift ring occupies a slightly eccentric position leftwardly of the primary rotor, as shown in Fig. 3 of the drawing.

The pump casing 10 terminates on either side in relatively flat boss formations 21 in which is formed a shaft-receiving bore 22. Extending through and slidably carried within the bores 22 are stub shafts 23 which are suitably and rigidly

connected at their inner ends, in diametrically opposed relation, to the shift ring 20. Each of the stub shafts 23 extends substantially outwardly from the pump casing 10 on either side thereof to be engaged by the flow-controlling mechanism, as will be hereinafter more fully described.

Secured to the right-hand boss formation 21 of the pump casing, as by means of cap screws 24, is a cylindrical spring housing 25 formed with an internal bore 26. Slidably carried in abutting relation to the right-hand stub shaft 23, and reciprocable within the internal bore 26 of the spring housing, is a piston-like end plate 27 which is engaged by one end of a coil compression spring 28. The opposite end of the spring 28 is abutted by a circular plate or collar 29 threadedly carried by the inner end of a screw-threaded adjusting shaft 30. The shaft 30 is rotatably carried in a bore 31 formed in the outer end wall of the spring housing 25. The shaft 30 extends outwardly from the housing and carries at its outer end a hand wheel 32 by which the shaft may be manually rotated. As will be understood, the rotation of the hand wheel functions to move the plate or collar 29 longitudinally of the bore 26 in a manner to adjust the tension of the coil spring 28, and consequently, to increase or decrease the force exerted by the spring 28 upon the end plate 27 and the right-hand stub shaft 23. Thus, it will be seen that the spring 28 functions to resiliently urge the flow-controlling shift ring 20 of the pump toward its extreme left-hand eccentric position, as shown in Figs. 1 and 2, providing for maximum displacement of fluid by the pump.

Mounted on the left-hand boss formation 21 of the pump casing, and rigidly secured thereto, as by means of cap screws 33, is a cylindrical plate 34 which is formed with a first cylinder bore 35 arranged in axial alignment with the shaft-receiving bore 22 of the casing 10. The bore 35 terminates at one end in a relatively diametrically enlarged annular port 36 which communicates with a radially extending inlet passage 37 formed in the plate 34 and terminating in a screw-threaded connection opening 37a disposed on the outer surface of the plate 34. Adjoining the first cylinder bore 35 and port 36 is a relatively smaller cylinder bore 38 which, in turn, terminates in an annular port 39. The port 39 also communicates with a second radially disposed passage 40 terminating at the periphery of the plate 34. Slidably carried within the larger cylinder bore 35 is a piston whose intermediate portion 41 is maintained in close-fitting wiping engagement with the walls of the bore 35, and which terminates at its inner end in a relatively reduced diameter projection 42 arranged to abut the outer end of the stub shaft 23. At its opposite end, the piston terminates in a relatively reduced diameter portion 43 which is carried in wiping engagement with the smaller diameter cylinder bore 38. The left-hand end faces of the pistons 41 and 43 provide pressure-responsive areas which are subject to fluid pressures introduced within the ports 36 and 39, respectively. As will be hereinafter more fully explained in connection with the operation of the present control, the pistons 41 and 43 function, in response to predetermined fluid pressures, to shift the flow control ring 20 of the pump in opposition to the coil compression spring 28, and toward a neutral or no-delivery position.

Rigidly secured to the outer surface of the plate 34, as by means of cap screws 44, is the inner end wall 45 of an elongated cylindrical spring

housing 46. The end wall 45 is provided centrally with a bore 47 arranged in axial alignment with the bores 38 and 35 containing the pistons 41 and 43. Extending through the bore 47, and slidably therein, is a plunger 48 which terminates at its outer end in a relatively reduced shaft portion 49. The shaft portion 49 extends through a bore 50 formed in a fluid-pressure-responsive piston 51, and is rigidly secured to the piston 51 by means of a threaded nut 52. The piston 51 is arranged to slide within the bore 46a of the housing 46 and is engaged on its rear side by one end of a coil compression spring 53. The spring 53 is somewhat heavier than the coil compression spring 28, which is mounted within the opposite housing 25, and functions, in the absence of counter-acting fluid pressures, to urge the plunger 48 rightwardly into close abutment with the outer end face of the piston 43 to shift the flow control ring 20 to a slightly left-hand eccentric position as shown in Fig. 3, at which position the piston 51 abuts the stationary end wall 45. The opposite end of the spring 53 engages a retaining collar 54 which is threadedly carried within a screw-threaded bore 55 formed in the outer end of the housing 46. For convenience, the cylindrical retaining collar 54 is provided centrally with a hexagonal bolt head 56 by which the collar 54 may be rotated through the use of the ordinary wrench, and the collar 54 may be locked in any adjusted position by means of an annular spanner nut 56a.

The piston 51 is formed on its opposite side with a relatively large pressure face or area 51a adjacent the end wall 45 which is responsive to pressure fluid introduced within the inner end of the housing 46 by way of a port 51b formed in the end wall 45 and having a radially extending passage or channel 51c terminating at the periphery of the housing 45. Thus, the piston 51 and its plunger or stop member 48 are arranged for movement inwardly of the pump assembly under action of the spring 53, but are subject to movement in the opposite direction in response to the introduction of fluid into the passage 51c and the inner end of the cylinder 46a under pressure sufficient to overcome the forces exerted upon the piston by the spring 53.

The end wall 45 is further formed in its central region with a leakage chamber or port 51d communicating centrally with the bore 47 in the end wall. The chamber 51d is provided with a radial outlet passage 51e which communicates with a reservoir, not shown. The chamber 51d serves to prevent the passage of fluid between the port 39 and the inner end of the cylinder 46a around the piston 48, and thus isolates the larger piston 51 from the smaller high pressure pistons or plungers 41 and 43.

As will be seen in Figs. 1 and 2, the inlet passage 40 communicating with the port 39 receives one end of a remotely extending conduit 47 whose opposite end communicates with one of the motor ports 58 of a spool-type distributing valve 59. The opposite motor port 60 of the valve 59 is connected by means of a conduit 61 with the passage 37 for the larger cylinder bore 35. The valve 59 is further provided with an inlet port 62 which is connected to receive fluid through a pilot line 63 communicating with a main pump discharge line 69 connected with the pump outlet passage 16. Further, the valve 59 is provided with an outlet or exhaust port 64 having a conduit 65 extending to an exhaust reservoir, not shown. The valve 59 is provided with a movable spool-

type valve member 66 which may be either mechanically or electrically controlled to establish communication between the inlet port 62 and either of the motor ports 58 or 60 while connecting the opposite motor port with the exhaust port 64, or may provide for the simultaneous connection of both motor ports with the inlet port 62. It will be understood that when it is desired that the pump be shifted toward its neutral position in response to a relatively extreme high pressure within the discharge or outlet of the pump, the valve 59 should be conditioned to establish communication between the pump discharge and the smaller port 39, as shown in Fig. 1, in view of the fact that the pressure-responsive face of the piston 43 is of smaller area than the pressure-responsive face of the larger piston 41, and consequently, a higher pressure within the pump discharge is necessary to force the pistons 41 and 43 rightwardly and the flow control ring 20 to a neutral position in opposition to the spring 28 when pressure is acting upon the smaller piston 43 alone. When it is desired to shift the pump automatically toward a neutral position in response to a lesser pressure within the pump discharge, the valve 59 may be conditioned to establish communication between the pump discharge and the larger port 36 where such pressure may act upon the relatively larger area provided by the piston 41. In the event that it is desired to shift the pump toward a no-delivery position in response to a still lesser pressure build-up within the discharge of the pump, the valve 59 may be conditioned to introduce fluid pressure into both ports 36 and 39 to react upon the composite areas of the pistons 41 and 43.

In operation, assuming that the pump is connected to supply pressure fluid to a double-acting ram, as shown at 68, and which may be employed to reciprocate one of the dies of a hydraulic press, the outlet passage 16 of the pump is connected with the main delivery line 69. Interposed within the line 69 is a reversing valve 70 having motor ports connected, respectively, with the ram-advancing and retracting areas of the ram 68, and operable selectively to introduce pressure fluid into either the ram-advancing area or the ram-retracting area while connecting the opposite area with exhaust. The port 51b and piston 51 are connected by way of a conduit 71 with the line 69. The distributing valve 59 is connected to receive pressure fluid from the main pump discharge line 69 through the conduit 63.

When the pump is idling at relatively low speed, the various parts of the control and pump occupy positions as shown in Fig. 3, wherein the flow control ring 20 is maintained in a slightly left-hand eccentric position providing for a relatively short pumping stroke of the pistons 41 and 43 and a substantially small displacement of fluid from the pump at low pressure. This short-stroke position is obtained due to the forces exerted by the relatively heavy spring 53 through the plunger 48, pistons 41 and 43, and the left-hand stub shaft 23 to the flow control ring 20. The force exerted by the spring 53 overcomes that exerted by the relatively lighter spring 28 until the piston 51 abuts the end wall 45, and further rightward movement of the flow control ring 20 under influence of the spring 53 is prevented. Thus, the pump is permitted to idle with little or no displacement of fluid by the pistons 41 and 43.

Assuming that it is desired to initiate an advancing stroke within the ram 68, the valve 70 is conditioned to establish communication be-

ween the ram-advancing area and the main discharge line of the pump and the speed of the pump is increased. Upon increase in the driving speed of the pump, the pistons 41 increase the pressure of fluid being discharged from the pump into the line 69. This increased pressure is transmitted to the face 51a of the piston 51 by way of the conduit 71, and when the pressure reaches a predetermined amount, say 150 p. s. i., sufficient to overcome the force exerted by the spring 53, the piston 51 and plunger 48 are shifted leftwardly to permit the spring 28 to shift the flow control ring 20 leftwardly to its full delivery position as shown in Figs. 1 and 2. The valve 59 may be conditioned so as to connect the smaller port 39 of the servo-motor control with the pilot line 63. The pump discharges pressure fluid through the main supply line 69 at full volume in view of the displacement of the flow control ring 20, the pistons 41 and 43, and the plunger 48 to their extreme left-hand positions by the spring 28. The ram 68 advances rapidly under the relatively high volumetric output of the pump until the same encounters resistance to further travel. As this resistance is encountered, the pressure in the pump discharge immediately increases, and this pressure is transmitted by way of the pilot line 63, valve 59, and conduit 57 to the smaller piston face 43. As the pressure within the smaller port 39 increases to a predetermined high pressure, the force exerted upon the smaller piston 43 overcomes the forces exerted through the variable tension spring 28 to move the flow control ring 20 rightwardly toward a neutral pressure-holding position, as indicated in Fig. 4. In this position the pump supplies sufficient fluid to the system to compensate for slippage or leakage and maintains a given high pressure throughout the circuit without endangering the pump or the various other elements in the circuit. At this time, the reversing valve 70 may be conditioned to introduce fluid pressure within the retracting area of the ram 68 and to exhaust the advancing area thereof to permit the ram to retract out of engagement with the work. Upon shifting of the valve 70, the pressure within the main discharge line 69 drops sharply to decrease the pressure acting upon the piston 43, thus permitting the spring 28 to once again shift the flow control ring 20 from its neutral position to full stroke position while sufficient pressure is maintained within the pump discharge to hold the piston 51 and plunger 48 in their left-hand positions. Thus, the ram 68 is retracted rapidly until reaching its upper position, at which time the pressure build-up within the pump discharge is transmitted to the piston face 41 and/or 43 of the servo-motor control to once again shift the pump to a no-delivery or holding position.

It will be understood that the differential pressure-responsive areas provided by the pistons 41 and 43, together with the distributing valve 59, provide a convenient means for adjusting the pressure at which the pump may be shifted from its full delivery position toward its neutral or pressure-holding position. As heretofore explained, the distributing valve 59 may be conditioned to supply pressure fluid selectively to either one of the pistons 41 or 43, or simultaneously to both pistons, and the greater the effective area subjected to the pressure of fluid discharged by the pump, the greater the force acting to shift the flow control member of the pump rightwardly against the action of the spring 28 at a given pressure. Thus, if the discharge of the

75 pump is connected to supply pressure fluid to the larger piston 41, a lesser pressure in the discharge of the pump is necessary to shift the pump toward its short-stroke position than is required when the discharge of the pump is directed to the smaller piston 43. By the same token, if both of the pistons 41 and 43 are subjected to pressures developed within the pump discharge, the pump will be shifted toward its short-stroke or no-delivery position at a still lesser pressure. It should here be noted that the plunger 48, which is under action of the spring 53, functions only when the pump is idling at relatively low speeds to maintain the flow control ring in its short-stroke position as shown in Fig. 3 and to provide for a small displacement of fluid from the pump when idling. The pistons 41 and 43 are sized in accordance with given desired pressure conditions, and in shifting the pump from a full delivery position to a neutral pressure-holding position, the same function independently of the plunger 48. Ordinarily, the tension of the spring 53 is adjusted so as to overcome the tension of the spring 28. However, as soon as the pressure build-up within the discharge of the pump reaches a predetermined amount, the piston 51 compresses the spring 53 and permits the flow control ring 20 to shift leftwardly in response to the forces exerted thereon by the spring 28.

30 In view of the foregoing, it will be seen that the present invention provides an improved and simplified fluid-pressure-responsive limit stop for the servo-motor controls of a variable delivery hydraulic pump which functions automatically 35 when the pump is idling to maintain the flow control member of the pump in an intermediate short-stroke position until the speed of the pump is increased to attain a predetermined pressure within the pump discharge; thereafter, the limit stop moves to a retracted position to permit the usual pump controls to actuate the flow control member of the pump during high pressure work operations.

40 Pump controls formed in accordance with the present invention may be applied with facility to present day pump constructions without requiring extensive modification thereto, and function to eliminate numerous and relatively complex valving arrangements and multiple stage pistons heretofore necessary to accomplish an automatic shifting of the pump to an intermediate short-stroke idling position.

45 While a single preferred form of the invention has been disclosed in detail, it will be understood that various modifications with regard to constructional details may be employed without departing from the spirit of the invention or the scope of the following claims.

50 I claim:
 1. In a control for regulating the volumetric output of a variable delivery hydraulic pump automatically in response to pressure conditions within the discharge of the pump, a flow-controlling member movable within said pump between 55 a no-delivery position and a full delivery position; spring means arranged on one side of the flow-controlling member of the pump and urging the latter toward its full delivery position; a fluid-pressure-responsive member engaging the flow-controlling member on the side thereof opposite said spring means; means for establishing communication between said fluid-pressure-responsive member and the discharge of the pump, said pressure-responsive member being operable, 60 in response to the attainment of a given high

pressure within the discharge of the pump, to move the flow-controlling member of the pump from its full delivery position to its no-delivery position; and other resiliently compressible spring means engageable with said pressure-responsive member only when the pressure within the discharge of said pump is below a given low pressure for causing said pressure-responsive member to move the flow-controlling member of the pump from its full delivery position to an intermediate delivery position.

2. In a control for regulating the volumetric output of a variable delivery hydraulic pump automatically in response to pressure conditions within the discharge of the pump, a flow-controlling member movable within said pump between a no-delivery position and a full delivery position; spring means arranged on one side of the flow-controlling member of the pump and urging the latter toward its full delivery position; a fluid-pressure-responsive member engaging the flow-controlling member on the side thereof opposite said spring means; means for establishing communication between said fluid-pressure-responsive member and the discharge of the pump, said pressure-responsive member being operable, in response to the attainment of a given high pressure within the discharge of the pump, to move the flow-controlling member of the pump from its full delivery position to its no-delivery position; other resiliently compressible spring means engageable with said pressure-responsive member only when the pressure within the discharge of said pump is below a given low pressure for causing said pressure-responsive member to move the flow-controlling member of the pump from its full delivery position to an intermediate delivery position; and means connected with said other spring means for varying the tension thereof and thereby to vary the given low pressure at which said other spring means is effective.

3. In a variable delivery hydraulic pump having a pressure outlet a flow control member movable in said pump between no-delivery and maximum delivery positions; spring means urging said flow control member toward its maximum delivery position; fluid-pressure-responsive piston means arranged to move said flow control member in opposition to said spring means, said piston means being in fluid communication with the pressure outlet of said pump and being responsive to a given high pressure at the pressure outlet of said pump for shifting said flow control member toward a neutral position; a fluid-actuated plunger engageable with said piston means and movable between a first position, limiting movement of said flow control member to an intermediate delivery position, and a second position, permitting said flow control member to be shifted to its maximum delivery position, said plunger having a pressure-responsive face in fluid communication with the pressure outlet of said pump operable to move said plunger, in response to a pressure at the pressure outlet of said pump substantially lower than said given high pressure, to its second position; and other spring means engaging said plunger and

operable, in the absence of said lower pressure acting on the face of said plunger, to shift said plunger to its first position in opposition to said first-named spring means.

- 5 4. In a variable delivery hydraulic pump; a flow-control member movable in said pump between no-delivery and maximum delivery positions; spring means engageable with said flow-control member on one side thereof for urging the latter toward its full delivery position; piston means engageable with the opposite side of said flow-control member and responsive to a predetermined high pressure output of said pump for shifting said flow-control member from a maximum delivery position toward its no-delivery position; a movable spring-pressed plunger engageable with said piston means to limit shifting movement of said flow-control member under influence of said spring means to an intermediate position between its no-delivery position and its maximum delivery position; and fluid-pressure-responsive means connected with said plunger and responsive to a given low pressure output of said pump substantially less than said first-named pressure output for moving said plunger to a position permitting shifting movement of said flow-control member by said spring means to its maximum delivery position.
- 10 5. In a variable speed, variable delivery hydraulic pump having a pressure outlet; a flow-control member movable between neutral and maximum delivery positions; spring means normally urging said flow-control member toward its maximum delivery position; a plunger arranged on the side of said flow-control member opposite said spring means and movable to shift said flow-control member from a maximum delivery position to an intermediate position short of said neutral position; a second spring means engaging said plunger and urging the latter to shift said flow-control member to said intermediate position in opposition to said first-named spring means; and fluid-pressure-responsive means connected with said plunger and responsive to a given low pressure at the outlet of said pump for moving said plunger to a position permitting free shifting movement of said flow-control member to its maximum delivery position under influence of said first-named spring means.
- 15 6. In a variable speed, variable delivery hydraulic pump; a flow control member movable in said pump between no-delivery and maximum delivery positions; spring means urging said flow control member toward its maximum delivery position; fluid pressure-responsive piston means connected with the flow control member of said pump and responsive to a predetermined high pressure within the discharge of said pump for shifting the flow control member of the pump to a no-delivery position in opposition to said spring means; and other spring means engageable with said piston means and operable when said pump is idling to cause said piston means to shift the flow control member of the pump to an intermediate delivery position.
